1**3,005,085****MECHANISM FOR HEATING ARTICLES PRIOR TO DEFORMING**

Peter S. Vosbikian and Thomas S. Vosbikian, Melrose, Pa. (20th and Oxford Sts., Philadelphia, Pa.)

Filed Jan. 7, 1960, Ser. No. 983

1 Claim. (Cl. 219—50)

The object of this invention is to devise a novel machine for heating a selected portion of an article prior to deforming into a desired shape.

A further object of the invention is to heat an article to be deformed in such a manner that an end portion will remain relatively cool so that it can be picked up by a bare hand for removal to a machine for accomplishing the deforming operation.

A further object of the invention is to devise a novel construction and arrangement of a sectional head which clamps the article in position in such a manner as to close an electric circuit by contact of the article with the head sections and to cause a longitudinal travel of the electricity through the selected portion of the article.

A further object is to insulate portions of the head sections from the article being clamped.

With the foregoing objects and other objects in view as will hereinafter appear in the detailed description and the appended claims, our invention comprehends a novel machine for heating a selected portion of an article prior to deforming the article.

It further comprehends a novel construction and arrangement of article clamping sections with novel means for insulating end portions of the article whereby the electric current passes in a longitudinal direction through the article to be deformed.

For the purpose of illustrating the invention, we have shown in the accompanying drawings a preferred embodiment of it which we have found in practice to give satisfactory and reliable results. It is, however, to be understood that the various instrumentalities of which the invention consists can be variously arranged and organized, and the invention is not limited, except by the scope of the appended claims to the exact arrangement and organization of these instrumentalities as herein set forth.

FIGURE 1 is a side elevation of a machine for heating an article prior to deforming.

FIGURE 2 is a front elevation.

FIGURE 3 is a sectional elevation taken through the head sections with an article to be heated in clamped position.

FIGURE 4 is a section on line 4—4 of FIGURE 3.

FIGURE 5 is a section on line 5—5 of FIGURE 3.

FIGURE 6 is a schematic view showing the travel of the cooling medium through the head sections.

FIGURE 7 is a sectional elevation of a modified form of head sections.

Similar numerals of reference indicate corresponding parts.

Referring to the drawings:

The invention in this case resides more particularly in the construction and arrangement of the head sections which when clamped with an article closes the circuit through a selected portion of the article. These head sections have been shown as replacements for the points of a conventional spot welder having a step down transformer and a foot treadle which controls the clamping

2

of an article between the head sections. It has, therefore been deemed unnecessary to illustrate and describe in full detail the construction of the spot welder.

The machine has a body portion or framework 1 provided with a foot treadle 2 operatively connected with an upper movable arm 3 to move it towards a stationary arm 4, said arms having their free ends inturned towards each other.

A heating and clamping head consists of an upper section 5 and a lower section 6.

The upper head section 5 has a body portion in the form of an arm or cross bar 7 having an upwardly extending tubular extension 8 to receive the terminal end of the upper arm 3, and opposite end portions have right angle cut-outs 9 and 10 respectively to receive the upper ends of vertically disposed end bars 11 and 12, respectively. The end bar 11 is insulated from the cross bar 7 by insulating material 13 and an insulating tube 14 insulates a fastening bolt 15 from the end bar 11. The end bar 12 is fixed to the cross bar 7 by a bolt 16.

The lower head section 16 has a cross bar 18 provided with an apertured, depending extension 19 for connection with the terminal end of the fixed arm 4 of the machine. The cross bar 18 has right angle cut-outs 20 to receive end bars 20 and 21 which project upwardly. The bar 20 is fixed to the cross bar 18 by a threaded rod 22 and nuts 23. Insulation 24 insulates a bolt 25 from crossbar 18 and end bar 21. A stop member 27 for positioning the article 28 is adjustable on the rod 22 and fixed in adjusted position by nuts 28'. In order to better position the article to be heated, the bars 11 and 12 are recessed at 17 and the bars 20 and 21 at 29.

In the modified form shown in FIGURE 7 the head sections are formed of right angle bars, the upper section having a cross bar 30 with a depending end bar 31. A second end bar 32 is secured by an insulating bolt 33 to the cross bar 30. In a similar manner, the lower head section 34 has an end bar 35 secured to it by an insulated bolt 36.

The end bars 11 and 12 of the upper head section have passages 37 for a cooling medium, and the bars 20 and 21 of the lower head section have cooling passages 38.

The schematic view of FIGURE 6 shows how the cooling medium passes through the head sections.

In the operation of the machine, the stop member 27 is set for the current to be applied to a selected portion of the article. When the foot treadle is depressed, the upper head section moves downwardly to clamp the article between the head section and to close the circuit which causes the current to pass to the specimen through cross bar 7 and end bar 12, through the selected portion of the specimen, end members 20 and 21, cross bar 18 to the return point of the electric current.

The flow of the current is in a longitudinal direction of the article or specimen to be heated. The result is that an end portion of the article is only slightly warm and can be picked up in the bare hand without injury to the operator.

Having thus described our invention, what we claim as new and desire to secure by Letters Patent is:

Mechanism for electrically heating a portion of an article prior to deforming, comprising an upper and a lower clamping head section, each consisting of an outer cross bar and spaced end bars at right angles to its respective cross bar, and having their free ends forming

clamping jaws, one end bar of one head section and the diagonally opposite end bar of the other section being insulated from their cross bar, said head sections having cooling passages for a cooling medium, a rod extending longitudinally from one head section, and a stop adjustable on said rod to selectively position a work piece between said clamping jaws, said head sections having terminals for an electric circuit and said circuit being closed by the clamping of a work piece between the clamping jaws.
